UNITED STATES PATENT OFFICE.

CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed June 11, 1924. Serial No. 719,896.

My invention relates to electric switches and particularly to switches of the oscillating rocker type. The object of my invention is to provide a simple and inexpensive construction adapted for handling relatively light current, such as is used for the lights of an automobile, although the device may be made of a size appropriate for heavier currents.

10 Fig. 1 is a side elevation of a switch in which my invention is embodied in one form;

Fig. 2 is a longitudinal section therethrough;

15 Figs. 3 and 4 are sections on the lines 3—3 and 4—4, respectively, Fig. 2;

Fig. 5 is a broken inverted plan view of the construction; and

20 Fig. 6 is a section on the line 6—6, Fig. 5.

The present switch comprises an insulating base block 15. Spaced apart at one end thereof, and projecting from its upper face, are spring contact straps 16 and 17, the offset lower ends of which are seated in recesses and engaged, respectively, beneath the nut 18 and the head of a tapped rivet 19.

The head of the screw 20, which takes into the nut 18, serves to hold in position and establish electrical connection with a strap 21 accommodated in a countersunk channel 22 in the lower face of the block, and extending from the screw bolt 20 to the tapped rivet 23 at the opposite end of the base.

Here, it is engaged beneath the wire terminal plate 24 secured by the rivet 23, into which takes the binding screw 25. The rivet 19 is directly engaged by the binding screw 26, and also holds in place the wire terminal plate 27. The lead wires for the

30 switch are thus spaced well apart, and as a matter of additional precaution the wire terminal plates are seated on ledges 28 and 29 depressed from the lower face of the base.

Upon the upper face of the switch base is an open lyre-shaped frame 30, secured in position by screws 31 passing through the base and arranged on opposite sides of the channel 22 in which the strap 21 is accommodated. Engaged between the free ends

35 of the frame uprights is the oscillating rock lever 32, the pivot pin 33 of which enters appropriate bearing apertures in the uprights and may be offset beyond the latter to rivet the parts together.

The switch-bar yoke 34 is provided with 55 offset bearing lugs 35 which engage in open bearings 36 afforded by inclined slots opening to one margin of the frame uprights. From the margin of one of the yoke arms, extends the switch bar 37, 60 at the free end of which is carried the switch piece 38, which passes through the switch bar 37 and is insulated therefrom by suitable washers 39. The bridge 40 of the yoke plays between stop lugs 41 and 42 offset from the base of the frame 30 and limiting the throw of the yoke.

Interposed between the bridge 40 of the yoke and the inner end of the oscillating switch lever 32 is the actuating spring 43. 70 In the form here shown the spring is in the nature of a bow spring, with one or more coils intermediate its ends 44 and 45. The end 44 is hooked over one margin of the bridge 40 of the yoke 34, while the opposite 75 end is offset and engaged in the notch 46 at the inner end of the oscillating lever 32. The spring is constantly stressed and the tendency of the arms is to move apart.

The casing 47 of the switch serves not only as a housing for the switch contacts and the operating mechanism, but also as the means by which the switch may be bodily supported in an apertured support 48, such as the dash board of a car, wall structure, or the like. It is integral throughout and formed up from sheet metal. The end walls 49 and 50 constitute offset continuations of the opposite side walls and are lap jointed at 51. The top 52 is integral with the side walls and is extended beyond the offset ends 49 and 50 of the latter to form projecting ears 53 adapted to overlie the supporting structure 48. The securing screws 54 by which the face plate 55 is secured above the casing 47, pass through notches 56 in the end lugs 53. The casing

80 preferably overlaps the upper margin of the base 15 and is accommodated in a peripheral recess 57. It is held in position by 85 studs 58 (Fig. 4) projecting outward from the yoke 30 and received in corresponding apertures 59 in the side walls of the casing. Guide grooves 60 formed at the margins of the casing serve the double function of leading the studs 58 into the holes 59, and of 90 camming the walls apart as the cover is shoved into position on the base. The split

95

and overlapped end walls permit the side walls to spring apart sufficiently to pass over the studs and snap into engagement with the latter as the holes 59 come into register with the studs. If desired the studs 58 may be offset and the cover thus riveted in position.

The entry of dust and dirt into the casing is effectively prevented by the dome-like

10 flange 61 on the operating lever 32, the curvature of the flange being such that in all positions of the lever the aperture 62 in the casing through which it passes is substantially closed.

15 The operation of the switch will be readily understood. In Fig. 2 the parts are shown in open-circuit position, with the switch block 38 lying between but out of engagement with the widely spaced legs of the contacts 16 and 17. If the operating lever 31

20 be swung upward on its pivot 33, the end 45 of the spring 43 is not only moved toward the opposite end 42 of the spring, thus further stressing the latter, but it is also shifted

25 across the axis of oscillation of the switch bar yoke 34. The effort of the spring is now exerted upon the latter to throw it from stop lug 41 to stop lug 42. This throw of the rocker swings the switch bar in the direction to cause the switch piece 38 to engage between contacts 16 and 17, and thus establishes the circuit through the switch. Obviously a reversal of the movement of

30 the contact lever swings the switch bar in the opposite direction, and again opens the circuit.

Various modifications in detail of construction and operation of the parts will readily occur to those dealing with the 40 switch, without departing from what I claim as my invention, while still retaining the advantages of economy in construction, simplicity of manufacture, and efficiency of operation which result from the present invention.

45 I claim—
1. In an electric switch an insulating base, a frame comprising a strap secured to the base with its ends extending away from the 50 base and angled toward each other, said strap having side flanges offset from its opposite margins between said ends, and also angled away from the base to form stops, a switch bar yoke pivoted between the up-

standing ends of the frame and having a 55 throw limited by said stops, an oscillating lever pivoted on said frame, and a U-spring, one arm of which is engaged by the end of said lever, and the other arm of which is engaged by the switch-bar yoke, said spring- 60 engaging end of the lever being shiftable across the axis of oscillation of the switch-bar yoke.

2. In an electric switch, a rectangular insulating base, switch contacts and mechanism mounted on one face of said base, a sheet metal casing folded to peripherally engage the base and secured thereon, and end flanges integral with said casing and forming end continuations of the casing top beyond the limits of the base to constitute a support for the base and associated structure. 70

3. In an electric switch, an insulating base, a switch mechanism mounted thereon and comprising a supporting frame with side members adjacent opposite sides of the base, a casing resting on the base and engaging elements of said side members of the frame engaging the opposite side walls of 80 the casing to secure it in position. 75

4. In an electric switch, an insulating base, a switch mechanism mounted thereon and comprising a supporting frame with side members, a casing resting on the base 85 and engaging elements of said side members of the frame to secure it in position, together with means integral with the casing for supporting the base and associated structure. 90

5. In an electric switch, a base, switch mechanism mounted thereon and comprising a frame with side members, in combination with a sheet metal casing for said mechanism, said casing having lap jointed walls 95 adapted to be sprung to permit the base to be adjusted on the base in locking engagement with detaining members on the side members of the switch frame.

6. In an electric switch, a sheet metal casing having integral top, side and end walls, certain of said walls comprising lapped sections adapted to be sprung for the purpose specified. 100

In testimony whereof I have signed my name to this specification. 105

CARL ERIC ANDERSON.
